UNITED STATES PATENT OFFICE.

JAMES E. WILLIAMSON, CHARLES E. COLLINS, AND JOHN B. GRAHAM, OF ALLEGHENY, PENNSYLVANIA.

ELECTRIC HEATER.

SPECIFICATION forming part of Letters Patent No. 556,524, dated March 17, 1896.

Application filed February 9, 1894. Serial No. 499,678. (No model.)

To all whom it may concern:

Be it known that we, JAMES E. WILLIAMSON, CHARLES E. COLLINS, and JOHN B. GRAHAM, citizens of the United States, residing at Allegheny, in the county of Allegheny and State of Pennsylvania, have invented certain new and useful Improvements in Electric Heaters; and we do hereby declare the following to be a full, clear, and exact description of the invention, such as will enable others skilled in the art to which it pertains to make and use the same, reference being had to the accompanying drawing, which forms a part of this specification.

Our invention belongs to that class of devices known as "electric heaters," in which a quantity-current of electricity is caused to flow through a high resistance in the conductive path, thereby causing heat to be developed at the place of resistance. The specific object in this case is to produce a heater of form, design, and size adapted to be lowered into an oil-well and therein heated by a current generated at the surface, for the purpose of softening and liquefying the solid and semi-solid products of petroleum occurring therein, which obstruct the flow, and thereby restoring the productive powers of the well.

Reference is made to the accompanying drawing, forming a part of this specification, showing a vertical sectional view of our improved heater and liquefier, in which—

a is a perforated tube or cylinder adapted to be lowered into an oil-well, closed at both ends with caps *b* *c*, and provided with insulated conductor-wires, one of which terminates at *e* and the other at *f*, as shown. The conductor *e*, which we make the positive conductor, is inclosed in the tube *h*, made of insulating material, which terminates at its lower extremity in the flaring or bell mouth *i*, which serves to prevent the immediate and rapid intermixture of the liquids entering the perforations in the upper part of the shell and those which have passed to the lower portion thereof.

The cylinder or shell is perforated through its wall to enable the fluids, consisting of impure oils, salts and hydrocarbonaceous material found therein to penetrate the same, and thus form a medium or path between the terminals, which, by its relatively-high resist-

ance to the passage of the current, causes a high temperature to be generated within the shell, whereby the oil and fusible hydrocarbons in the vicinity are softened and liquefied.

To aid the passage of the resistance-current, in case the fluids penetrating the perforated shell are insufficiently charged with salts, we place a charge of some salt, as sodium or ammonium chloride, in the bottom of the lower cap, as shown in the drawing in the dotted mass in the lower cap *c*.

The cylinder is lowered into the well by a cord or line in the usual manner.

We are aware that electric heaters on the resistance principle are no novelty, and that modified forms of such heaters for use in oil-wells are old, and we do not claim such broadly; but

What we claim, and desire to secure by Letters Patent, is—

1. An electric heater for oil-wells, comprising a perforated cylinder or shell, closed at both ends with caps *b*, *c*, having a charge of salt in the lower cap, and provided with an insulated positive conductor-terminal, as *e*, inclosed in a bell-mouthed tube *h*, and an insulated negative conductor-terminal *f*, whereby when the interior space of the shell becomes filled through the perforations by the fluids of the well, carrying a saltin solution as specified, the passage of the current through the same from terminal to terminal develops heat along the path of high resistance thus afforded, and liquefies the semisolid hydrocarbons in the vicinity, substantially as specified.

2. The electric heater for oil-wells, consisting of the perforated shell *a*, screw-caps *b*, *c*, positive insulated conductor-terminal *e*, negative insulated conductor-terminal *f*, and tube *h* with bell-mouth *i*, all substantially as shown and described.

In testimony that we claim the foregoing we hereunto affix our signatures this 5th day of February, A. D. 1894.

JAS. E. WILLIAMSON. [L. S.]
CHAS. E. COLLINS. [L. S.]
JOHN B. GRAHAM. [L. S.]

In presence of—

ALBERT J. WALKER,
C. A. WILLIAMS.
